SPARK PLUG CLEANING DEVICE

Robert Roy Shelton, Chattanooga, Tenn., assignor to Frank J. Nolan, Chattanooga, Tenn.

Application October 5, 1932, Serial No. 636,384

2 Claims. (Cl. 51—8)

This invention relates to improvements in devices for cleaning spark plugs.

The object of the invention is to simplify the construction of the apparatus and the mode of operating or manipulating the device. More specifically, the apparatus comprises means for projecting a sand laden blast of air against a spark plug to clean the latter and a second blast of air to remove any particles of sand that may have adhered to the plug. In the present instance, the ducts for these two air blasts are, in part, formed in a single fitting where they communicate with a single source of supply of compressed air and a two-way valve is provided in said fitting whereby the flow of air through both ducts is controlled by the single valve. This simplifies the construction and operation of the device and, likewise, tends to reduce the cost of production.

20 Another object is to baffle the air blasts to obtain a maximum effect thereof on the spark plug being cleaned. In connection with this feature of the invention, the baffle is so constructed that it also aids in precipitating the sand from the air
25 currents after the sand laden blast of air has been projected against the spark plug.

With these and other objects in view, the invention consists in certain details of construction and combinations and arrangements of parts, all as will hereinafter be more fully described and the novel features thereof particularly pointed out in the appended claims.

In the accompanying drawing:

Fig. 1 is a vertical sectional view illustrating the preferred embodiment of the present invention:

Fig. 2 is a horizontal section on the line 2—2 of Fig. 1.

Fig. 3 is an elevational view of the fitting and valve for the air blast ducts:

Fig. 4 is a sectional view on the line 4—4 of Fig. 3.

In the embodiment of the invention illustrated in the present instance, there is a shell or casing 45 10 provided with an aperture 11 in which is secured a perforated, flexible washer 12. The spark plug 13, to be cleaned, is inserted in the opening in the washer 12 as shown in Fig. 1. The flexible washer 12 is retained in the opening in the casing 50 by an annular metal ring, the opening in which is of larger diameter than the orifice in the washer and the orifice in the washer is of less diameter than the diameter of the threaded portion of the spark plug, so that the washer may 55 flex when a plug is inserted therein but will fric-

tionally retain the plug. Projecting transversely through the casing wall, opposite aperture 11, is an air pipe 14. This pipe is enclosed by a tubular nozzle 15 formed integral with the casing and the interior of said nozzle communicates with a depending pipe 16 whose lower extremity is located in a body of sand or other cleaning material 17 in a reservoir formed by the bottom of the casing. The bottom of the casing is inclined as at 18 to facilitate feeding of the sand to said pipe 16. 10

18 to facilitate feeding of the sand to said pipe 16. 10
A second air pipe 19 also projects into casing
10 substantially parallel to pipe 14. This second
pipe does not extend into nozzle 15 but projects
a considerable distance beyond said nozzle into
proximity to the spark plug 13. At the exterior
15 of casing 10, pipes 14, 19 are connected to a fitting 20, pipe 14 communicating with a duct 21
in the fitting and pipe 19 with a duct 22. Ducts
21, 22 communicate with a duct 23 which is adapt-
ed to be connected with a suitable source of sup-
ply of compressed air. Fitting 20 is secured to
the casing by a threaded nipple 25. A two-way
valve 24 is provided in fitting 20 and, as will be
apparent air may be delivered through either of
pipes 14, 19 at the will of the operator by simply
turning said valve in one direction or the other.
In cleaning the spark plug, air is first delivered
through pipe 14. The passage of the air through
nozzle 15 will cause sand to feed upward through
feed pipe 16 and be projected in the blast of air
from said nozzle, against the spark plug. This
removes foreign matter from the spark plug, after
which valve 24 is turned to cut off air from pipe
14 and deliver it to pipe 19. Air issuing from
pipe 19 free of sand will be projected against the
spark plug and remove from the latter any par-
ticles of sand that may have adhered thereto. 30
35

In order to obtain the full effect of the sand laden blast of air issuing from nozzle 15, there is provided a baffle 26. Preferably, this baffle is tubular and of cylindrical formation with the upper portion of its wall of greater length than the lower portion thereof. Baffle 26 extends transversely of casing 10 from aperture 11 toward nozzle 15, with the latter arranged axially of the baffle wall or in line with the spark plug in opening 11. The upper portion of the baffle extends over nozzle 15 but its lower portion terminates short of said nozzle. The baffle not only concentrates the sand laden blast of air on the plug being cleaned but the currents of air returning from against the plug along the upper portion of the baffle have to travel a considerable distance before escaping to the upper portion of casing 10. In this way they are given more time in which

to lose their momentum and consequently there is a greater opportunity for the sand to precipitate therefrom. Consequently, there is less likelihood of the screens 27, through which the air 5 passes before escaping through opening 28 from the casing, clogging up with the sand. Also, the lower portion of baffle 26 being comparatively short, sand cannot readily accumulate therein.

The screens 27 are secured within the casing 10 by being clamped between said casing and the casing cover 28 which, in turn, is held in place by a bail-like member 30 pivoted in the casing and adapted to frictionally engage over the top of said cover.

15 What I claim is:

1. In a device for cleaning spark plugs, a casing having an opening in one wall thereof, a washer of resilient material located on said wall over the opening and having an opening therein 20 of smaller diameter than the opening in said wall for receiving a part of a spark plug, a second washer of metal partly covering the resilient

washer and having an opening therein of larger diameter than the opening in the washer of resilient material and means located in the casing for forcing cleaning material against the plug. 5

2. In a spark plug cleaning device, a casing having an opening in one side wall in which a spark plug may be inserted, a reservoir for cleaning material in the lower portion of said casing, means comprising a nozzle extending into said casing for projecting a blast of air and cleaning 10 material against a spark plug positioned in said opening, a horizontally disposed tubular baffle encircling said opening, the upper portion of said baffle projecting from said opening toward the opposite wall of the casing beyond the discharge 15 end of said nozzle and terminating adjacent said opposite side wall and the lower portion of said baffle terminating short of said nozzle, and a screened passage above said baffle through which air escapes from said casing. 20

ROBERT ROY SHELTON.
